UNITED STATES PATENT OFFICE.

MORITZ SACHS, OF NUREMBERG, BAVARIA, GERMANY.

HOLDER FOR PENCILS.

SPECIFICATION forming part of Letters Patent No. 364,303, dated June 7, 1887.

Application filed March 15, 1886. Serial No. 195,334. (No model.) Patented in Germany November 19, 1885, No. 35,867, and November 21, 1885, No. 36,478; in England December 17, 1885, No. 15,533, and in Austria-Hungary July 2, 1886.

To all whom it may concern:

Be it known that I, MORITZ SACHS, a subject of the King of Bavaria, residing in Nuremberg, Bavaria, Germany, have invented a new and useful Improvement in Holders for Pencils and Similar Objects, (for which I have obtained patents in England, No. 15,533, and dated December 17, 1885; Germany, No. 35,867, November 19, 1885; patent of addition thereto, No. 36,478, of November 24, 1885, and Austria-Hungary July 2, 1886,) of which the following is a specification.

My invention relates to the contrivance for feeding forward, withdrawing, stopping, and releasing the movable core or tube of holders for pencils, pens, and other small instruments.

In describing the invention reference will be made to the accompanying drawings, of which—

- 20 Figure 1 is an axial section of an improved pencil-holder, the movable core being withdrawn; and Fig. 2, an axial section of the same, the movable core projecting. The remaining figures represent modifications and details.
- 25 The outer tube, *a*, contains the black-lead tube *b*, fastened at its lower extremity. The black-lead tube *b* is furnished with a long slit, *b'*, and two lateral recesses, *b''*. To the tube *b* is fixed a small tube, *c*, furnished with elastic cheeks *c'*, which catch into the recesses *b''*. The tube *b* contains the black-lead *d*, over which lies freely the slide *g* with the catch *g'*. The latter projects from the tube slit *b'* and catches into the screw-thread *h'* of the tube *h*. This tube *h* is adapted to revolve the tube *b*, and also (as in pencil-holders with so-called "English guiding") to be displaced longitudinally thereon. It is raised at the projection *h''* by the spiral spring *i*, resting on the bent portion *a'* of the tube, acts in raised position, Fig. 1, with its bent lower extremity, *h''*, on the clipping-cheeks *c'*, and projects with its upper end the tube-head *h'* from out of the tube *a*. By pressing on the tube-head *h'*, Fig. 2, the slide *g g'* is moved longitudinally within the tube *h h'*, and thereby the black-lead released from the clipping-cheeks is fed forward. When the pressure on the tube-head *h'* ceases, the black-lead remains in the forward position, if the holder lie horizontally, while the tube *h h'*, with the slide *g g'*, gets
- 55 back again into the original position and clips the black-lead fast again. By a further pressure on the head *h'*, while the point of the holder is held upward, the lead can be brought into the original position, as in Fig. 1. The slide *g g'* being also adapted to be shifted by turning the tube *h h'*, this slide can, with the varying length of the black-lead, always be put in a position which allows the black-lead 60 to be fed forward in the requisite amount for use by pressing the tube-head *h'*. The black-lead, of course, can also be fed forward for use by merely turning the tube *h*.
- 55 Figs. 3, 4, 5, and 6 represent likewise a 65 holder with feed mechanism. This device is equal to that of Figs. 1 and 2, with the only exception that in the holder shown by Figs. 3, 4, 5, and 6 the black-lead *d* is rigidly connected with the slide *g g'*, and the small tube *c* with 70 the clipping-cheeks *c'* and the tube-recesses *b''* are omitted. Owing to the connection of the black-lead *d* with the slide *g g'* the black-lead *d*, if only the arrangement shown by Figs. 1 and 2 were applied, could be propelled by longitudinally displacing the tube *h*, but could 75 not be retained in its forward position. For attaining the latter purpose a stopping and releasing device is arranged, which, as it will be shown, may also be applied to holders with 80 differently-constructed feed mechanism.
- 75 The stopping and releasing device consists, (Fig. 3,) first, of the elastic catches *k*, fixed to the tube *a*; second, of a tube, *m*, secured on the tube *h*, and provided with an outstanding ring, 85 *m'*, preferably of an ogival or conical form, adapted to arrive between the catches *k* and press the same apart, so as to arrive in front of them; third, of the ring *n*, sliding on the neck *h''*, above the said conical part *m'*, and 90 having an exterior diameter somewhat larger than the base of the said part *m'*, its travel on the said neck *h''* being limited downwardly by the said conical part *m'* and upwardly by the flange *h''*.
- 95 By shifting forward the sleeve *h h'*, and therefore the slide *g g'* with black-lead *d*, by pressure on the head *h'* the ring *m'* passes between the points of the catches *k* and the latter rest on the neck *h''*, and the base of the ring *m'* is 100 pressed back onto the said points by the action of the spring *i*, so that the tube *h h'*, and there-

fore the black-lead d , (or pen, crayon, or the like) is held firmly in its forward position. When the black-lead is to be released, the head h' is pressed farther downward into the case, 5 by which means the flange h^6 arrives on the ring n and forces the latter downward between the points of the springs k . On releasing the head h' the slide $h h'$, with all the parts $h^6 h^6 m' n$, is moved upward in the case by the spring 10 i . By this means the base of the ring m' arrives against the ring n , forcing the latter from between the catches k , which slide off onto the sides of the ring m' , so as to free the latter, and the whole mechanism resumes the position 15 shown in Fig. 3.

Fig. 6 is a cross-section of Fig. 5 along line A B. As also this arrangement permits the tube $h h'$ to turn on the tube $b b'$, the slide $g g'$ can also here, when the length of the black-lead changes, be brought into a position which 20 allows the black-lead to be shifted forward for use by pressing the tube-head h' . Moreover, here the black-lead can also be fed forward as well as withdrawn by merely turning the tube 25 $h h'$. The feeding forward and withdrawal of the black-lead can here be effected in any position of the holder by pressing as well as by turning.

I do not confine myself to any particular 30 shape or number of catches, k . Also, I may replace the screw-thread pressed into the material of the sleeve h by a helical rail fixed to or formed on the inner surface of said sleeve.

The arrangement of the separate parts of 35 the stopping and releasing device may also be different from that shown by Figs. 3, 4, and 5. Figs. 7, 8, 9 represent such a modification of a holder, with a part, h , simply adapted to slide longitudinally, which, as in the holders 40 hitherto described, is in connection with a spiral spring, i . Here the catches are fixed to the part h and tend to expand or separate from each other by their elasticity. The slide-surface m , with the projection m' , however, is situated on the stationary tube a —that is to say, they are formed by this very tube, and the movable ring n may be displaced within the limits m' and h^6 , Fig. 7. The arrangement is here made so that by displacing 45 the part h (which may carry a pen, o , or a black-lead and such like) the catches k , which press against the sliding surface m , slide on the latter until they arrive behind the projection m' , where they spread so as to abut when 50 the pressure ceases on the said projection and be retained thereby, as shown in Fig. 8. When the part h is again fed forward, the catches k are pressed together inwardly, Fig. 9, by the ring n , situated at the limit h^6 , and 55 they are held in this position by the ring n until the latter is suddenly thrown upward with the parts $k k$ by the spiral spring i , when the pressure on h^6 ceases and is stripped off when abutting against the projection m' by the 60 catches k , which thereby get on the sliding surface.

With holders in which the movable part h is not turned the movable part n need not be ring shaped. This part may, for instance, if the stopping device is arranged as shown by 70 Figs. 3, 4, and 5, consist of two small parts of a ring connected by a pin, which parts are guided and stopped by a pin working in a slot of the neck h^6 of the tube.

In all figures analogous parts are indicated 75 by the same letters.

What I claim is—

1. In holders for pencils and similar objects, the combination, in an outer casing, a , of a tube, b , fixed at its lower end to said casing 80 and having a slot, b' , with a screw-threaded sleeve, $h h'$, adapted to turn around and to slide along said tube, a slide, g , sliding in said tube, and having a projection, g' , passing through the slot b' and embracing the screw-thread h' , 85 together with a helical spring, i , adapted to raise the tube $h h'$, substantially as and for the purpose set forth.

2. The combination, in an outer casing, a , of a tube, b , fixed at its lower end to said casing, 90 and having a slot, b' , clipping-tongues c' , the slide g , with projection g' , the screw-threaded sleeve $h h'$, gearing with said projection g' , and adapted by its downward motion to disengage, and by its upward motion to engage, the said clips c' , and the spiral spring i , adapted to retain the sleeve $h h'$, so as to operate said clips c' , substantially as and for the purpose set forth. 95

3. In an outer casing, the combination, with 100 the lead-carrier, of a neck, h^6 , operated reciprocally with said carrier, a ring, m' , at the lower end of said neck, a flange, h^6 , at the upper end of said neck, a ring, n , sliding loosely on said neck and of larger diameter than the 105 ring m' , stationary projecting spring-catches k , adapted to slide over said ring m' and fall onto said neck, and a helical spring, i , adapted to lift the lead-carrier.

4. The combination, with the outer casing, 110 a , the slotted tube $b b'$, fixed thereto, the slide $g g'$, and helically-threaded sleeve $h h'$, of a neck, h^6 , arranged on said sleeve, a ring, m' , on the lower end of said neck, a flange, h^6 , on the upper end of said neck, a ring, n , sliding 115 on said neck, spring-catches k , fixed to the casing a and adapted to slide over said ring m' and rest on said neck, and the helical spring i , adapted to lift the sleeve $h h'$, substantially as and for the purpose set forth. 120

5. In an outer casing, the combination, with the lead-carrier, of spring-catches k , operated reciprocally with said carrier, a cylindrical chamber, h^6 , stationary in the casing, an inwardly-projecting flange, h^6 , at the lower end 125 of said chamber, an inwardly-extending ring, m' , at the upper end of said chamber, a ring, n , loosely sliding in said chamber, and a helical spring, i , adapted to raise the lead-carrier.

6. The combination, with the outer casing, 130 a , slotted tube $b b'$, fixed therein, slide $g g'$, and helically-threaded sleeve $h h'$, operating said

slide, of spring-catches *k*, fixed to said sleeve, a cylindrical chamber arranged in said casing *a*, an inwardly-extending ring, *m*, at the upper end of said chamber, a flange, *h*^o, at the lower end of said chamber, a ring, *n*, loosely sliding in said chamber, and a helical spring, *i*, adapted to raise the sleeve *h* *h*^o, substantially as and for the purpose set forth.

In testimony whereof I have signed this specification in the presence of two subscribing witnesses.
